UNITED STATES PATENT OFFICE.

HARRY L. BEACH, OF COSHOCOTON, OHIO.

THERMOMETER.

1,132,426.

Specification of Letters Patent. Patented Mar. 16, 1915.

Application filed June 30, 1914. Serial No. 848,273.

To all whom it may concern:

Be it known that I, HARRY L. BEACH, a citizen of the United States, residing at Coshocton, in the county of Coshocton and State of Ohio, have invented a new and useful Thermometer, of which the following is a specification.

This invention relates to improvements in thermometers.

10 The principal object of the present invention is to provide a suitable frame or casing for a thermometer, wherein the chance for accidental or malicious breaking of the tube or bulb thereof is reduced to a minimum.

15 Another object is to provide a separate holder forming a tube and bulb-carrying means at the rear or interior face of the frame or casing, whereby the thermometer 20 may be readily applied to the casing by the use of a suitable number of screws.

25 A further object of the invention is to provide a thermometer casing of the class described which is adapted to receive suitable advertising matter and, at the same time, may be cheaply manufactured by merely stamping any suitable sheet metal into the desired form and then providing the same with the usual vertical slot to expose the thermometer tube.

30 With these and other objects in view the invention consists in the construction and novel combination of parts hereinafter fully described, illustrated in the accompanying drawing, and specifically pointed out in the claims hereto appended, it being understood that various changes in the form, proportion, size and minor details of construction, within the scope of the claims, may be 35 sorted to without departing from the spirit or sacrificing any of the advantages of the invention.

35 In the drawing, in which like reference characters designate corresponding parts in each of the several figures: Figure 1 is a front view of the improved device. Fig. 2 is a rear view thereof. Fig. 3 is a central vertical sectional view of the same. Fig. 4 is a transverse section of Fig. 1, about mid-way of the length thereof.

40 The device of the present invention consists in providing a frame or casing 1 preferably stamped of suitable sheet metal of sufficient strength and thickness to maintain 45 its form and to withstand any hard usage to which it may be subjected. This frame,

as shown in the drawing, is of a vertically elongated rectangular shape, though it is to be understood that any form or contour capable of receiving and housing the thermometer and the carrying means therefor may be adopted.

45 The frame 1 is provided with an inwardly directed flange 2, extending around the four sides thereof and of sufficient depth to space 50 the front face 3 of the frame away from the wall or other surface to which the device may be applied, a distance greater than the thickness of the thermometer tube and bulb carrying means 4 to be presently described. 55 The frame is also provided with a central vertically arranged sight opening in the form of a slot 5 extending throughout the major portion of the length of the frame, and is for the purpose of exposing to view 60 the tube 6 of the thermometer proper, which may be of the ordinary construction. Flanking the side or sides of the slot or sight opening 5 are arranged the customary 65 graduations or degrees 7, to indicate the 70 temperature in the usual manner, and these marks or degrees may be formed in any desired way. At the lower end of the slot or sight opening 5, the sheet metal from which the frame member 1 is formed is struck up 75 or pressed outwardly to provide an approximately elliptically shaped offset cover or housing 8 adapted to receive the mercury 80 bulb 9 of the thermometer, when the holder 85 4 therefor is applied to the frame 1 in a 90 manner to be described.

85 The thermometer support or holder 4 consists of a comparatively narrow block or strip of wood of a length sufficient to extend from a point adjacent the shoulder of the 95 said mercury bulb 9 to a point slightly beyond the upper end of the tube 6. The holder is provided on its front face with a central longitudinal recess 10 of a depth equal to the diameter of the said tube, and 100 extending upwardly from the lower edge of the holder 4 a distance equal to the length of the thermometer tube, said slot terminating at its upper end in a slight inwardly or rearwardly directed cavity or enlargement 105 11. This cavity 11 is adapted to receive the rearwardly extending point 12 with which the upper end of the tube 6 is provided, and thus prevents any relative longitudinal movement between the holder and the thermometer. Thin metallic straps or plates 13 110 are employed to hold the tube within the

wooden block or holder, small tacks or brads 14 being used to secure the straps to said block. It will thus be seen that the block 4, carrying the thermometer, is capable of being handled without any danger of displacement of the thermometer tube therein, and that it may be readily applied to the rear or inner face of the frame or casing 1 by the simple use of a plurality of screws 15, as 5 shown in the drawing, which pass through necessary holes or eyes provided in the frame 1 adjacent the sight opening 5, on each side thereof, the screws penetrating the wooden block or holder 4 and thus securely binding 10 the two together. Any number of screws may be employed. The frame 1 is further provided near the top and bottom with centrally arranged, aligned openings 16, through which nails or screws may be passed for the 15 purpose of securing the device to any suitable support. Ample space may be provided at the top and bottom of the front plate or face of the frame to be imprinted with advertising matter. It will be observed that 20 with this construction and arrangement of parts, the tube and bulb of the thermometer are arranged wholly within the casing or frame, and that it is practically impossible to give, either accidentally or maliciously, a 25 blow to the same that would cause damage or breakage to the thermometer, and that the same is effectually shielded, so as to prevent accumulation of snow, ice, or dirt to interfere with the ready reading of the thermometer.

The device is of such simple construction that the same may be cheaply manufactured and given away as an advertising medium, as it is susceptible of enamel or other ornamentation to augment its appearance.

By the described method of attaching the tube and bulb in place, the thermometer may be shipped through the mails without danger of breakage, and this is one of the special 45 advantages of the invention.

What is claimed is:—

1. A thermometer comprising a frame provided with an inwardly extending marginal flange forming a hollow casing with the rear side open, and having a central longitudinally disposed slot and an offset cover at the lower end of the slot, a separate block having a longitudinal recess of a depth to re-

ceive the thermometer tube, leaving the bulb projecting from the lower end, means for 55 securing the tube within the recess of the block, and means for securing the block to and against the rear face of the frame within the marginal flange, so as to present the thermometer tube in line with the longitudinal slot and the thermometer bulb within 60 the offset cover.

2. A thermometer comprising a frame provided with an inwardly extending marginal flange forming a hollow casing with the rear side open, said frame having a longitudinally disposed slot and an offset cover at the lower end of the slot, a block having a longitudinal recess of a depth to receive a thermometer tube with the bulb projecting below the lower end of the block, said thermometer tube having an inwardly projecting point at its upper end to engage a cavity in the block, straps to hold the tube in the recess of the block, and screws for securing 70 the block to and against the rear face of the frame within the marginal flange so as to present the thermometer tube in line with the longitudinal slot but wholly back of the rear face of the front part of the casing and 75 the thermometer bulb within the offset cover.

3. A thermometer comprising a frame provided with an inwardly extending marginal flange forming a hollow casing with the rear side open, said frame having a longitudinally disposed slot and an offset cover at the lower end of the slot, a block having a longitudinal recess of a depth to receive a thermometer tube with the bulb projecting below the lower end of the block, means to 80 hold the tube in the recess of the block, and screws for securing the block to and against the rear face of the frame within the marginal flange, so as to present the thermometer tube in line with the longitudinal slot 85 but wholly back of the rear face of the front part of the casing and the thermometer tube within the offset cover.

In testimony, that I claim the foregoing as my own, I have hereto affixed my signature in the presence of two witnesses.

HARRY L. BEACH.
